UNITED STATES PATENT OFFICE.

GEORGE W. SHIEBLER, OF BROOKLYN, NEW YORK.

DESIGN FOR A SPOON-HANDLE.

SPECIFICATION forming part of Design No. 15,808, dated February 10, 1885.

Application filed October 7, 1884. Term of patent 7 years.

To all whom it may concern:

Be it known that I, GEORGE W. SHIEBLER, of Brooklyn, in the county of Kings and State of New York, have invented and produced a 5 Design for Handles of Spoons and Analogous Articles, of which the following is a specification.

In the drawings, Figure 1 is a photograph of the surface of a spoon-handle; and Fig. 2 is a section at *x x*, showing the shape of the handle.

This design relates to the handles of spoons and analogous articles. The outline of the handle is a taper from the broad end down 15 to the shank, and the surface of the handle is composed of tapering ribs, there being two converging grooves, *a a*, between the ribs, and the ends of the ribs are nearly semicircular, as at *b b*. The handle on the under 20 side is channelled to correspond to the ribs upon the upper surface, so that the handle is of the sectional shape shown in Fig. 2. The

handle is ornamented with indentations at *e*, cross-bars *f*, leaflets *g*, arches *h*, and fluting *k*, and scrolls *l*, leaflets *n*, and bars *o*. There 25 are also flutes at *p*, scroll-work at *q*, and indentations at *r*.

I claim—

1. The design for the handle of a spoon or similar article, consisting of ribs and intermediate grooves tapering from the broad end to the narrow shank and the nearly semicircular ends to the ribs, substantially as described and shown. 30

2. The design for the handle of a spoon or similar article, consisting of ribs and intermediate grooves and the surface ornamental patterns, substantially as described and shown. 35

Signed by me this 2d day of October, A. D. 1884.

GEO. W. SHIEBLER.
